DESIGN FOR A PERFUME SACHET HOLDER

Franklin Pierce, New York, N. Y.

Application December 15, 1944, Serial No. 117,104

Term of patent 7 years

(Cl. D86—10)

To all whom it may concern:

Be it known that I, Franklin Pierce, a citizen of the United States, residing at New York, in the county of New York and State of New York, have invented a new, original, and ornamental Design for a Perfume Sachet Holder, of which the following is a specification, reference being made to the accompanying drawing, forming a part thereof, in which

I claim:

The ornamental design for a perfume sachet holder, as shown.

FRANKLIN PIERCE.
